Specification for Design.

Patented Sept. 6, 1921.

Application filed September 19, 1919. Serial No. 325,026. Term of patent 7 years.

To all whom it may concern:

Be it known that I, WILLIAM H. MOORE, Jr., a citizen of the United States, residing at Little Rock, in the county of Pulaski and State of Arkansas, have invented a new, original, and ornamental Design for an Emblem, Badge, or Similar Article to be Applied to Ties, Shirts, and Similar Articles of Wearing-Apparel, of which the following is a specification, reference being had to the accompanying drawing, forming a part thereof.

The figure is a perspective view showing my design applied to a piece of fabric for wearing apparel.

I claim:

The ornamental design for an emblem, badge, or similar article to be applied to ties, shirts, and similar articles of wearing apparel, as shown.
